UNITED STATES PATENT OFFICE.

JOHN WALDHEIM, OF ELIZABETH, NEW JERSEY, ASSIGNOR TO UNDERWOOD ELLIOTT FISHER COMPANY, OF NEW YORK, N. Y., A CORPORATION OF DELAWARE.

TYPEWRITING MACHINE.

Application filed January 3, 1924. Serial No. 684,127.

This invention relates to typewriting machines of the continuous billing or fan-fold type, one form of which is shown in the patent to Wernery & Smith, No. 1,132,055, dated March 16, 1915, in which a web or pack which may be composed of separate plies or of plies attached at their edges, is fed together with interleaved carbon-sheets around the platen, and provision is made for shifting the carbons from a section of the superposed plies in which typing has been completed to the next unused section on which typing is to be effected. Usually each ply of a web or pack carries a succession of printed forms, and the forms on the superposed plies are in register.

For certain classes of work to be done in a fan-fold or continuous billing machine, it is a desideratum to be able to type upon any one of a plurality of webs or packs, to be able to change quickly from one pack to another, and to be able to type upon more than one of said packs at the same time.

An object of the invention is to provide a fan-fold or continuous billing machine in which a change may be effected rapidly from typing on one web or pack to typing on another, from typing on one pack to typing on more than one pack, and from typing on more than one pack to typing on any selected pack.

In the embodiment of the invention herein disclosed, provision is made of two carbon-carriers which may be arranged one behind the other, and which preferably may be mounted on the same track. To avoid interference between the packs extending from the carbon-carriers to the platen, the carbon-blades of the two carbon-carriers may be supported at different heights. Preferably the pack from the rear carbon-carrier passes to the paper-table at the rear of the platen above the forward carbon-carrier, and at such a height thereabove as not to interfere with the rearwardly-folded forward end of the lower pack when the forward carbon-carrier is in its extreme forward position.

A feature of the invention consists in the provision of means to detain the forward carbon-carrier in its extreme forward position when the rearward carbon-carrier is to be used alone, and to detain the rearward carbon-carrier in its extreme rearward position

while the forward carbon-carrier is in use. When, therefore, the forward carbon-carrier is to be used alone, the rearward carbon-carrier is moved rearwardly and placed under the control of said detaining means, which preferably acts automatically when the rearward carbon-carrier reaches its rear-most position. When the rearward carbon-carrier is to be used the forward carbon-carrier is moved to its extreme forward position and there detained by an automatically acting detaining device. It should be understood that when either of the carbon-carriers is to be used the extent of the rearward movement thereof may be determined by suitable means such as an adjustable stop.

Another feature of the invention consists in the provision of means for connecting the carbon-carriers so that they may be used as a single carbon-carrier. Preferably such connecting means is so constructed as to become effective automatically when the carbon-carriers are brought together.

To operate the carbon-carriers use may be made of a single carbon-carrier handle, which may readily be detached from either of said carbon-carriers and attached to the other; the single handle under certain conditions enabling only the active one of the carbon-carriers to be actuated.

Other features and advantages will herein-after appear.

In the accompanying drawings,

Figure 1 is a side elevation, partly in section, showing the invention applied to an Underwood fan-fold machine, the forward carbon-carrier being in use.

Figure 2 is a detail view showing the manner of attaching the carbon-carrier handle to the carbon-carrier in use.

Figure 3 is a view similar to Figure 1, showing the arrangement of the parts when the rear carbon-carrier is in use.

Figure 4 is a top plan view of a portion of the mechanism shown in Figure 1.

Figure 5 is a detail view showing the connection between the two carbon-carriers when both are used at the same time.

Upon depression of keys, not shown, type-bars 10 are swung upwardly and rearwardly to cause types 11 thereon to strike against a platen 12 journaled by means of an axle 105 13 in arms 14 of a platen displacing frame

15 comprising a paper-table 16 to receive work from the platen and having attached thereto a gage-bar 17 on which a leading-edge gage 18 is adjustably secured by means 5 of a set screw 19.

The arms 14 of the platen-shifting frame are pivoted at the front on a shaft 20 supported in a carriage 21 comprising a cross-member 22 and carrying at the rear of the 10 platen a shaft 23 on which the rear ends of the arms 14 of the platen-displacing frame 15 rest, said carriage also including a rear paper-table 24 extending over said shaft 23 to guide work to the platen 12, around the 15 bottom of which the work is guided by a paper-apron 25 between the platen and front and rear feed-rolls 26 and 27, respectively. To hold the platen-displacing frame 15 in 20 normal position, provision may be made of hooks 28 fixed on the shaft 23 and normally held by spring means, not shown, in engagement with pins 29 on the arms 14, the release of the hooks being effected by means of a handle 30 preferably formed as an extension 25 of one of said hooks 28.

The cross-bar 22 has secured thereto, by suitable brackets, a rearward extension 31 of the carriage comprising front and rear cross-members 32 and forwardly and rearwardly extending rods 33 carrying flat rails 34 to co-operate with grooved rolls 35 pivoted on a base 36 of a carbon-carrier 37.

As herein illustrated, provision may be made of two such carbon-carriers 37, one 30 behind the other. Preferably the forward carbon-carrier is lower than the rearward carbon-carrier and comprises at each end thereof stepped blocks 38 carrying carbon blades or holders 39, to which are attached 35 the rear ends of carbon-sheets or carbons 40 interleaved between continuous webs or plies 41, which may extend upwardly from a suitable source of supply, around a transverse guide 42 at the rear end of said carriage-extension 31, forwardly past the carbon-blades 39 and between the platen and the rear paper-table 24 and paper-apron 25 to the printing line. Preferably the webs 41 are provided with successive forms superposed in 40 register, and successive sets of superposed forms may be typed and severed by a knife 43 in the usual manner.

The rearward carbon-carrier may be provided with stepped blocks 44 of such height 45 that the carbon-blades 39, supported thereby, are elevated to a considerable extent above the carbon-blades of the forward carbon-carrier 37, leaving a clearance or gap within which may be tucked the idly-folded-back end of the lower web, Figure 3, above the reach of the lower web which extends from lower guide 42 forwardly to the lower carbon-carrier. Attached to the carbon-blades on the rearward carrier 37 are carbon-sheets 45 of a second set interleaved be-

tween plies 46 of a second set supported at the rear of the carriage-extension by means of a transverse guide or rod 47. The plies 41 and 46 may be guided laterally by edge-gages 48 and 49, respectively. 70

In case it is desired to use only the forward carbon-carrier, as illustrated in Figure 1, the webs and interleaved carbon-sheets in the rearward carbon-carrier 37 are folded rearwardly, and the rearward carbon-carrier is moved rearwardly and detained in its rearmost position by suitable means such as a spring-detent 48^a on the base thereof engaging the rear transverse rod 32 and yieldably detaining the carbon-carrier in 75 rearmost position. The forward carbon-carrier may be limited in its rearward movement by means of a detachable stop 49^a placed on one or both of the rails 34 and secured thereto by a set-screw 50. When the rearward carbon-carrier is to be used, the forward carbon-carrier may be detained by a 80 detent 48^a in its Figure 3 position and the stop 49^a may be shifted to its Figure 3 position. 85

Inasmuch as ordinarily only one of the carbon-carriers is to be used at one time, provision may be made for using one carbon-carrier handle 51 for both carbon-carriers. To this end the carbon-carrier handle 51 90 may have a laterally-extending flange 52 provided with a slot 53 to receive the shank of a headed stud 54, fixed in the base 36 of each carbon-carrier, and the shank of a second stud 55. It will be seen that the shank of the stud 55 is of such diameter that, when the handle 51 is forced rearwardly, the split end of the flange 52 will be spread and then the sides thereof will snap back substantially to normal position with the shank 100 of the stud 55 fitting in the cutouts 56. With this arrangement it will be evident that the carbon-carrier handle may be easily detached from one carbon-carrier and attached to the other when desired. 105

As illustrated in Figure 5, the carbon-carriers 37 may be connected by suitable means such as a spring-detent 57 secured at one end to the base of the rearward carbon-carrier and having a projection 58 to enter a recess 59 in the base of the forward carbon-carrier when the two carbon-carriers are brought together in co-operative relation. The platen may then be displaced and sets of web-plies and interleaved carbon-sheets 110 may be passed between the rear paper-table and the platen, and, after suitable adjustment of the web-plies, the platen may be restored to its normal position and typing effected on both sets of webs, the two carbon-carriers being actuated as a single unit. 115

Preferably, as shown in Figures 1 and 3, the carbon-holders 39 of the forward carbon-carrier lie below the horizontal plane determined by the rear edge of the rear paper- 120

table 24 and the carbon-holders of the rearward carbon-carrier lie above this plane.

Variations may be resorted to within the scope of the invention, and portions of the 5 improvements may be used without others.

Having thus described my invention, I claim:

1. In a continuous billing typewriting machine, the combination with a platen around 10 which may be fed two packs of web-plies and interleaved carbon-sheets, of means for presenting separate work-packs to the platen, including a platen-carriage having a rearward extension, two carbon-carriers, one for 15 each set of carbon-sheets interleaved between the plies of said packs, mounted one behind the other for reciprocation on said extension, each carbon-carrier with its carbon-sheets and pack forming a separate unit, means 20 for detaining said rearward carbon-carrier unit idly in its rearmost position when the forward carbon-carrier unit is to be used, the rear carrier mounted at a sufficient elevation above the forward carrier to leave a clearance 25 gap for the idly-folded-back web of the forward carrier, an upper web-guide in rear of the rear carrier, and a lower web-guide in rear of the front carrier.

2. In a continuous billing typewriting 30 machine, the combination with a platen around which may be fed two packs of web-plies and interleaved carbon-sheets, of a platen-carriage having a rearward extension, two carbon-carriers, one for each set of carbon-sheets interleaved between the plies of 35 said packs, mounted one behind the other for reciprocation on said extension, and means effective automatically upon movement of the forward carbon-carrier to its extreme 40 foremost position to detain it in such position and upon movement of the rearward carbon-carrier to its rearmost position to detain it in such position.

3. In a continuous billing typewriting 45 machine, the combination with a platen around which may be fed two packs of web-plies and interleaved carbon-sheets, of a platen-carriage having a rearward extension, two carbon-carriers, one for each set of carbon-sheets interleaved between the plies of 50 said packs, mounted one behind the other for reciprocation on said extension, and means effective automatically upon bringing the carbon-carriers together to connect them and 55 cause them to act as a single carbon-carrier.

4. In a continuous billing typewriting 60 machine, the combination with a platen around which may be fed two packs of web-plies and interleaved carbon-sheets, of a platen-carriage having a rearward extension, two carbon-carriers, one for each set of carbon-sheets interleaved between the plies of 65 said packs, mounted one behind the other for reciprocation on said extension, means effective 70 automatically upon bringing the car-

bon-carriers together to connect them and cause them to act as a single carbon-carrier, and means effective automatically to detain the combined carbon-carriers in either forward or rearward position.

5. In a continuous billing typewriting machine, in combination, a platen, a platen-carriage having a rearward extension, a plurality of carbon-carriers on said extension, one behind the other, a single carbon-carrier handle, and means for connecting said handle to said carbon-carriers comprising a slot in the handle to interchange with holding studs on the carbon-carriers so that the handle may readily be detached from one carbon-carrier and attached to the other carbon-carrier.

6. In a continuous billing typewriting machine, in combination, a platen, a platen-carriage having a rearward extension, a plurality of carbon-carriers on said extension, a single carbon-carrier handle, means for connecting said handle to said carbon-carriers in such a manner that the handle may readily be detached from one carbon-carrier and attached to the other carbon-carrier to actuate the same to retract the carbon-sheets connected therewith, and means for connecting said carbon-carriers so that said handle may be used to actuate both of the carbon-carriers at the same time.

7. In a continuous billing typewriting machine, the combination with a platen around which may be fed a plurality of packs of web-plies and interleaved carbon-sheets, of means for presenting separate work-packs to the platen, including a platen-carriage having a rearward extension, a plurality of carbon-carriers, one for each set of carbon-sheets and individually reciprocable on said extension, each carbon-carrier with its carbon-sheets and pack forming a separate unit, means for connecting the carbon-carriers to be operated jointly as a single unit, and separate introductory guides for the two webs, to clear one web from the other, sufficient clearance being provided vertically between the two carriers to afford a clearance for the idly-folded-back end of the lower web.

8. In a continuous billing typewriting machine, the combination with a platen around which may be fed a plurality of packs of web-plies and interleaved carbon-sheets, of means for presenting separate work-packs to the platen, including a platen-carriage having a rearward extension, a plurality of carbon-carriers, one for each set of carbon-sheets, reciprocable on said extension, each carbon-carrier with its carbon-sheets and pack forming a separate unit, means for detaining any of said units in idle position during the activity of the other unit and separate introductory guides for the two webs, to clear one web from the other, sufficient clearance being provided vertically be-

tween the two carriers to afford a clearance for the idly-folded-back end of the lower web.

9. In a continuous billing typewriting machine, the combination of a carriage, a platen on said carriage around which any one of a plurality of packs of work-sheets may be fed with interleaved carbon-sheets, means for presenting separate work-packs to the platen, including an extension to travel with said carriage, a plurality of carbon-carriers individually reciprocal on said extension and each carrying a set of carbon-sheets, each carbon-carrier with its carbon-sheets and pack forming a separate unit, one of said carbon-carriers being operative at a time, means for holding either unit idle during the activity of the other unit, and a single finger-piece connectible to actuate any of said carbon-carriers.

10. In a continuous billing typewriting machine, the combination of a carriage, a platen on said carriage around which any one of a plurality of packs of work-sheets may be fed with interleaved carbon-sheets, an extension to travel with said carriage, a plurality of carbon-carriers, one for each set of carbon-sheets, one of said carbon-carriers being active at a time, a detachable finger-piece connectible to the active one of the carbon-carriers, and resilient detents to hold the carbon-carriers in their inactive positions.

11. In a web-typing machine, the combination of a platen, means for presenting

separate work-packs to the platen, including a carriage, a carriage-extension, carbon-carriers on said extension one behind the other, each carbon-carrier with its carbon-sheets and pack forming a separate unit, means for rendering the units either jointly or individually active, at will, including releasable means for connecting said carriers, and separate introductory guides for the two webs, to clear one web from the other, sufficient clearance being provided vertically between the two carriers to afford a clearance for the idly-folded-back end of the lower web.

12. In a continuous billing typewriting machine, the combination of a platen, a carriage, means for presenting separate work-packs to the platen, including a carriage-extension, said extension comprising rails, a plurality of carbon-carriers arranged behind each other on said rails, each carbon-carrier with its carbon-sheets and pack forming a separate unit, and each carbon-carrier comprising a set of carbon-carrying blades, the blades of each set being in step-like relation, the sets in the various units being also in step-like relation with reference to each other, a single finger-piece interchangeable with either one of the carbon-carriers, and separate introductory guides for the two webs, to clear one web from the other, sufficient clearance being provided vertically between the two carriers to afford a clearance for the idly-folded-back end of the lower web.

JOHN WALDHEIM.
